UNITED STATES PATENT OFFICE.

LINCOLN A. LOWE, OF WATSON, MISSOURI.

STOVEPIPE-FASTENER.

No. 827,876.

Specification of Letters Patent.

Patented Aug. 7, 1906.

Application filed July 21, 1905. Serial No. 270,715.

To all whom it may concern:

Be it known that I, LINCOLN A. LOWE, a citizen of the United States, residing at Watson, in the county of Atchison and State of Missouri, have invented a new and useful Stovepipe-Fastener, of which the following is a specification.

This invention relates to stovepipe-fasteners, and has for its object to provide a device of the class embodying new and improved features of convenience, cheapness, reliability, and adaptability.

A further object of the invention is to provide a stovepipe-fastener having means for engaging the inner and outer walls of the chimney and the inserted end of the pipe and arranged to be adjusted with respect to such points of engagement.

A further object of the invention is to provide a stovepipe-fastener wherein the pipe is secured to the chimney by a spring capable of adjusting itself to the expansion caused by heat or otherwise.

A further object of the invention is to provide in a stovepipe-fastener means for holding the pipe-collar in contact with the outer wall of the chimney.

With these and other objects in view the present invention consists in the combination and arrangement of parts, as will be hereinafter fully described, shown in the accompanying drawings, and particularly pointed out in the appended claims, it being understood that changes in the form, proportion, size, and minor details may be made without departing from the spirit or sacrificing any of the advantages of this invention.

In the drawings thus employed, Figure 1 is a view in side elevation of the improved stovepipe-fastener applied to a pipe and chimney, shown in vertical section. Fig. 2 is a perspective view of the improved stovepipe-fastener. Fig. 3 is a view in side elevation of the improved fastener, showing another way of attaching to the pipe.

Like characters of reference indicate corresponding parts in all of the figures of the drawings.

In its preferred embodiment the improved stovepipe-fastener forming the subject-matter of this application is adapted to be used in connection with a chimney, as 10, and a pipe, as 11, of the usual and ordinary construction. The fastener comprises a strip 12, preferably of metal, one end of which is

coiled laterally, as at 13, while the opposite end is provided with a loop or hook 14, to which is secured a helical spring 15. Near the end and adjacent the coil 13 the strip is slotted obliquely, forming the lugs 16 for engagement with the inserted end of the pipe.

Upon the strip 12 is slidably mounted a clip 17, with the lips 18 folded over the longitudinal edges of the strip and carrying a tongue 19 for engaging the chimney walls or for holding the pipe-collar 19^a. To secure the fastener to the pipe, a wire 20 may encircle the elbow and form a loop 21, engaging the hook 22 of the spring 15. When there is a long run of riveted pipe, a small metal strip 23 may be inserted between the joints of pipe and, extending back along the pipe, as at 24, engage the hook 22.

In mounting the device it is first ascertained how far the pipe should extend into the chimney-opening and the lugs 16 arranged to stop the pipe at such point by rolling or unrolling the coil 13, thereby changing the location of the lugs. The end 13 is then inserted through the collar 19^a and into the chimney-opening. The pipe 11 is then inserted through the collar and into the chimney-opening and into engagement with the lugs 16. The strip 12 and the pipe are then drawn outwardly until the coil 13 contacts with the inner wall of the chimney, when the clip 17 is moved up, so that the tongue 19 contacts with the collar 19^a and the lips 18 closed tightly upon the strip by the use of tweezers or otherwise. The fastener being firmly secured in the chimney, the wire 20 or the strip 23 is put in place and the spring 15 connected, thereby holding the pipe against the lugs 16, which being firmly fixed do not permit the pipe sliding into the chimney and shutting off the draft or falling outwardly.

Having thus described the invention, what is claimed is—

1. A stovepipe-fastener comprising a strip having means at one end thereof for engagement with the inner wall of a chimney and provided with a stop adapted to engage the adjacent end of the stovepipe, said chimney-engaging means being adjustable with respect to the stop.

2. A stovepipe-fastener comprising a strip having one end thereof coiled for engagement with the inner wall of a chimney and provided with a stop adapted to engage the adjacent end of the stovepipe, said coil being adjustable with respect to the stop to vary

the length of the strip, and pipe-attaching means carried by the opposite end of said strip.

3. A stovepipe-fastener comprising a strip having means at one end thereof for engagement with the inner wall of a chimney and provided with a stop adapted to engage the adjacent end of the stovepipe, said chimney-engaging means being adjustable with respect to the stop, and a tongue slidably mounted on the strip and adapted to engage the outer wall of the chimney.

4. A stovepipe-fastener comprising a strip having one end thereof coiled for engagement with the inner wall of a chimney and provided with spaced upwardly-extending lugs adapted to engage the adjacent end of the stovepipe, said coil being adjustable with respect to the lugs, a tongue slidably mounted on the strip and adapted to engage the outer wall of the chimney, and pipe-attaching means carried by the opposite end of said strip.

5. A stovepipe-fastener comprising a strip having means at one end thereof for engagement with the inner wall of a chimney and provided with a stop adapted to engage the adjacent end of the stovepipe, said chimney-engaging means being adjustable with respect to the stop, a tongue slidably mounted on the strip and adapted to engage the outer wall of the chimney, and a yieldable connection between the opposite end of the strip and the pipe.

6. The combination with a chimney and pipe, of a strip adapted to be inserted in the chimney-opening and provided with means for engagement with the inner wall of said chimney, means carried by the strip and adapted to engage the adjacent end of the pipe, said chimney-engaging means being adjustable with respect to the pipe-engaging means, and means carried by the strip for engaging the outer wall of the chimney.

7. The combination with a chimney and pipe, of a strip having one end thereof coiled for engagement with the inner wall of the chimney and provided with spaced lugs adapted to engage the adjacent end of the pipe, said chimney-engaging means being adjustable with respect to the lugs, a tongue slidably mounted on the strip and adapted to engage the outer wall of the chimney, means for securing the tongue in adjusted position, and a yieldable connection between the opposite end of the strip and the pipe.

In testimony that I claim the foregoing as my own I have hereto affixed my signature in the presence of two witnesses,

LINCOLN A. LOWE.
